PLUG-IN POWER SUPPLY

Joseph A. Mas, 3 Maple Way Drive,
Woodbury, N.Y. 11797

Filed Mar. 13, 1967, Ser. No. 6,191

Term of patent 14 years

(Cl. D26—15)

FIGURE 1 is a perspective view of a plug-in power supply in accordance with the invention.

FIGURE 2 is a top view of the structure shown in FIGURE 1.

FIGURE 3 is a side elevational view of the structure shown in FIGURE 1.

FIGURE 4 is a bottom view of the structure shown in FIGURES 1 through 3.

FIGURES 5 and 6 are end elevational views of the structure shown in FIGURES 1 through 3.

The broken lines are for illustrative purposes only.

I claim:

The ornamental design for a plug-in power supply, as shown and described.
